UNITED STATES PATENT OFFICE.

LEONORA H. WARD, OF WEATHERFORD, OKLAHOMA.

BLACKBOARD-ERASER CLEANER.

Application filed December 28, 1925. Serial No. 78,039.

The present invention relates to a highly novel yet simple device for facilitating the cleaning of black board erasers.

One of the important objects of the present invention is to provide a device of the above mentioned character which will enable black board erasers to be cleaned in an expeditious and sanitary manner.

A further object is to provide a device of the above mentioned character which includes a grating over which is adapted to be reciprocated the erasers to be cleaned, a holder being provided for the erasers for clamping a number of the erasers so as to facilitate the cleaning of several erasers at one time, the cleaning of the erasers being effected by rubbing the same across the grating.

A still further object is to provide a device of the above mentioned character which is simple in construction, inexpensive, strong, and durable, and further well adapted to the purpose for which it is designed.

Other objects and advantages of the invention will become apparent during the course of the following description taken in connection with the accompanying drawing.

In the accompanying drawing forming a part of this application, and in which like numerals designate like parts throughout the several views:

Figure 1 is a top plan view of the device embodying my invention showing the manner in which the same is supported on the outside of a window.

Figure 2 is a transverse section taken approximately on line 2—2 of Figure 1, and

Figure 3 is a side elevation of the device showing the frame supported within a dust collecting receptacle, the latter being shown in section.

In the drawing wherein for the purpose of illustration is shown the preferred embodiment of my invention, the numeral 1 designates a substantially rectangular shaped frame, and extending over the top thereof is the grating 2 which is preferably formed of wire mesh material. The edges of the grating are secured to the top of the frame at the sides and ends thereof by means of the strips shown at 3.

For the purpose of preventing any possibility of the grating 2 sagging, there are provided strips 4 which are constructed of flat metal, the same extending longitudinally of the frame, directly beneath the grating,

the ends of the strips being disposed downwardly and secured between the inner faces of the respective ends of the frame 1, as illustrated at 5, with reference more particularly to Figure 2.

A pair of longitudinally extending guide rods 6 are disposed adjacent the respective sides of the frame, the respective ends of each of the guide rods being disposed downwardly as illustrated at 7 and being secured to the respective ends of the frame 1 in any suitable manner so that the guide rods extend above the grating in spaced relation thereto.

The eraser holding means comprises the pair of complementary flattened bars or plates 8 and 9, the same being provided adjacent their respective ends with suitable openings to accommodate the respective guide rods 6 whereby said bars are adapted for slidable movement on the rods across the top of the grating 2.

A suitable cover or lid 12 having depending flanges formed at its edges is placed over the back of the erasers. Suitable clamping bolts extend through registering openings provided therefor in the bars whereby the bars will engage the respective sides of the depending flanges formed on the cover or lid 12 and thereby clamp the cover therebetween when the wing nuts 11 are threaded on the threaded ends of the bolts and are turned in one direction. It is of course understood that the heads of the bolts engage the outer side of the bar 8.

The eraser holding means is of such size as to accommodate a number of erasers, and as is shown more clearly in Figure 2, four erasers are placed between the bars.

A suitable handle 13 is associated with the lid or cover 12, and provides a means whereby the eraser carrying member and the erasers supported therein may be reciprocated across the grating so that the bottoms of the several erasers will rub across the grating, and as a result the crayon dust will be removed from the erasers.

When black board erasers are cleaned in a room, in order to prevent the crayon dust escaping into the air in the room, a suitable dust collector, such as is shown at 14 is provided, the same being of such construction as to enable the frame 1 to fit snugly therein and rest on the bottom thereof. Thus the crayon dust which is shaken out

from the erasers will be collected within the pan 14, thereby enabling black board erasers to be cleaned in a sanitary manner.

In order that the device may be used for 5 cleaning black board erasers on the outside of a window, there is provided the supporting frame 15, the same extending outwardly from the window sill in a horizontal position, the inner portion of said supporting 10 frame being secured to the window sill as at 16. The frame 1 of the black board cleaning device is adapted to extend transversely across the supporting frame, and for the purpose of preventing the displacement of 15 the device from the supporting frame, there is provided the pivoted catches 17 on the sides of the frame 1, the same being adapted to engage the respective sides of the supporting frame. The catches which are secured 20 on the forward sides of the frame 1 will cooperate with the forward end of the supporting frame 15 to prevent the outward sliding movement of the frame 1.

The provision of a black board eraser 25 cleaner of the above mentioned character will enable a number of erasers to be cleaned at one time and furthermore in an expeditious manner. The simplicity of my device furthermore enables the several parts to be 30 readily set up in position for use, and will furthermore be inexpensive in its construction, yet strong and durable.

While I have shown the preferred embodiment of my invention it is to be understood 35 that minor changes in the size, shape and arrangement of parts may be resorted to without departing from the spirit of the invention and the scope of the appended claims.

Having thus described the invention, what 40 I claim as new is:—

1. A device for cleaning black board erasers comprising a substantially rectangular frame, a grating supported thereon, a 45 pair of longitudinally extending guide rods supported at their respective ends on the ends of the frame adjacent the sides of the latter, said guide rods being spaced above the grating, and eraser holding means adapt- 50 ed for reciprocatory movement across the

grating, said means including a pair of spaced bars, the ends thereof being provided with openings whereby said bars are adapted for slidable movement on the guide rods, adjusting bolts associated with the bars, the bottoms of the erasers being adapted to rub across the grating when the eraser holding means is actuated.

2. A device for cleaning black board erasers comprising a substantially rectangular frame, a grating supported thereon, a pair of longitudinally extending guide rods supported at their respective ends on the ends of the frame adjacent the sides of the latter, said guide rods being spaced above the grating, and eraser holding means adapted for reciprocatory movement across the grating, said means including a pair of spaced bars, the ends thereof being provided with openings whereby said bars are adapted for slidable movement on the guide rods, adjusting bolts associated with the bars, the bottoms of the erasers being adapted to rub across the grating when the eraser holding means is actuated. 60
